INVENTOR.
Martin E. Thomas,

BY

Geo. P. Kimmel. ATTORNEY.

UNITED STATES PATENT OFFICE.

MARTIN E. THOMAS, OF PLANO, TEXAS, ASSIGNOR, BY DIRECT AND MESNE ASSIGNMENTS, OF THREE-FOURTHS TO G. G. ACREE AND ONE-FOURTH TO H. N. THOMAS, BOTH OF PLANO, TEXAS.

DRILL BIT.

Application filed March 2, 1923. Serial No. 622,394.

To all whom it may concern:

Be it known that I, MARTIN E. THOMAS, a citizen of the United States, residing at Plano, in the county of Collin and State of Texas, have invented certain new and useful Improvements in Drill Bits, of which the following is a specification.

This invention relates to drill bits, more particularly to devices of this character employed in drilling deep oil wells, artesian wells and the like, and has for one of its objects to improve the construction and increase the efficiency and utility of devices of this character.

Another object of this invention is to provide a device of this character in which means are provided for adjusting the cutting elements as they are worn away to maintain the drilled hole of a uniform size throughout.

With these and other objects in view the invention consists in certain novel features of construction as hereinafter shown and described and then specifically pointed out in the claim, and in the drawings illustrative of the preferred embodiment of the invention.

Figure 1 is a side elevation, and

Figure 2 is a front view, of one of the improved devices, the latter view being partly in section,

Figure 3 is a bottom plan view.

The improved device comprises a stock or body 10 having a continuous longitudinal bore 11 and with one end bevelled in opposite directions at each side of a continuous transverse medial line 12, whereby flat bevelled faces 13 and 14 are formed each occupying one half of the diameter of the stock.

Formed in each of the bevelled faces 13 and 14 are a plurality of threaded sockets 15 to receive binding screws 16 whereby cutting disks 17 are adjustably coupled to the bevelled faces.

Initially the cutting disks will be coupled to the innermost sockets, and then as the disks are worn away by the action of the rock through which the drill is operating, the disks may be reground and then coupled to the outermost sockets, whereby the cutting edges of the reduced disks will be maintained in position to cut substantially the same sized hole throughout the whole length of the well.

Then again a drill bit is produced which may be quickly changed to cut holes of two or more diameters without structural change in the bit, merely changing the location of the holding bolts 16, as will be obvious.

The improved device is simple in construction, can be made of any desired size and is comparatively inexpensive to manufacture.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention what is claimed as new is:

A drill bit adapted to be attached to a tubular rod and including a stock having a continuous longitudinal bore and with the end of the stock formed with reversely bevelled faces with the juncture of the bevelled faces forming a continuous medial line transversely of the stock and transecting the bore, and cutting disks revolvably mounted respectively on the bevelled faces of the stock with their contiguous cutting edges overlapping the transverse medial line at opposite sides of the discharge of the bore.

In testimony whereof, I affix my signature hereto.

MARTIN E. THOMAS.
